UNITED STATES PATENT OFFICE.

WILLIAM M. SAUSSER AND JACOB M. SAUSSER, OF SCHUYLKILL HAVEN, PENNSYLVANIA.

VICTUAL-PROTECTOR.

SPECIFICATION forming part of Letters Patent No. 709,048, dated September 16, 1902.

Application filed March 14, 1902. Serial No. 98,245. (No model.)

To all whom it may concern:

Be it known that we, WILLIAM M. SAUSSER and JACOB M. SAUSSER, residents of Schuylkill Haven, in the county of Schuylkill and State of Pennsylvania, have invented certain new and useful Improvements in Victual-Protectors; and we do hereby declare the following to be a full, clear, and exact description of the invention, such as will enable others skilled in the art to which it pertains to make and use the same.

This invention relates to devices in the nature of false bottoms for boilers, pots, kettles, and the like and which are preferably termed "victual-protectors," since in use they are adapted to serve that purpose by keeping material being cooked away from the bottoms themselves, which frequently become overheated.

The main object of the invention is to improve this class of devices, which in certain forms are old.

In the accompanying drawings, Figure 1 is a plan view of the device. Fig. 2 is a central vertical section thereof and of a boiler or kettle in which the device is placed in position of use. Fig. 3 shows the device in a different form of receptacle. Fig. 4 is a central vertical section of a modification.

In the preferred form the protector is a sheet-metal disk 1, the main or central part of the body of which is flat, but which has stamped in it several projections 2, which are convex on the upper side of the disk and concave below. In the same portion of the body of the disk are several convex projections 3 on the opposite (the lower) side of the disk and forming concavities on the upper side of the disk and which serve as legs. There should be

several of the lower projections—say four—ninety degrees apart, just inside the crimped band. When further support is necessary, a like downward projection may be formed at the center of the disk, (see Figs. 1, 2,) though generally this is not required, but may be to keep the disk from sagging at the center when material resting thereon is heavy. The body of the disk has numerous perforations 4 distributed among the described projections.

Around the outer edge of the disk and an in-

tegral part thereof is a crimped or ribbed band-like part 5. The ribs extend substantially radially (though preferably at a small angle to the radii) of the disk, and the angle thereof may be changed without departing from the principle of the invention. This ribbed band portion is preferably bent upward a little from the main plane of the disk, though this is not essential.

6 is a flat-bottomed cooking-kettle, in which the victual-protector is shown in position of use. The downward convex projections 3 form legs or supports for the device, holding it a trifle above the kettle-bottom. The upper projections are adapted to hold material being cooked from intimate extended contact with the body of the disk. The ribs of part 5 strengthen the disk and also serve to keep material, as meat, from resting flat on the surface of the disk in its edge portion and form small passages for fluid under the meat where it rests thereon.

Fig. 3 shows the protector in position of use in a kettle having a bottom ledge 7, in which case the lower or leg projections 3 may or may not reach the central part of the bottom. The upward bend of the ribbed portion 5 and also the ribs reduce the area of contact between the kettle and the protector and reduce danger of burning material being cooked.

Fig. 4 shows that the ribbed band 5' may be horizontal instead of being bent up, as above described. This figure shows the main part of the body of the protector convex, with convex projections 2 on its upper side and convex projections 3, adapted to serve as legs, on its lower side. The lower projections in this form of device are not always essential, but are preferably used.

We claim—

1. A victual-protector for use in the bottom of cooking vessels, consisting of a sheet-metal plate, there being several rounded projections on the upper side of the protector-plate, and integral therewith, and perforations in the plate distributed among said projections.

2. A victual-protector, for use in the bottom of cooking vessels, consisting of a sheet-metal perforated plate, there being several rounded projections on the upper side of the protec-

tor-plate and integral therewith, and similar but reversed projections on the opposite side of the plate and serving as legs.

3. A victual-protector, for use in the bottom 5 of cooking vessels, consisting of a sheet-metal perforated plate, there being several rounded projections on the upper side of the protector-plate and integral therewith, and an integral ribbed portion surrounding the part 10 having said projections.

4. A victual-protector, for use in the bottom of cooking vessels, consisting of a sheet-metal perforated plate, said plate having integral projections, and a ribbed portion around its 15 periphery.

5. A victual-protector, for use in the bottom of cooking vessels, consisting of a circular perforated plate having integral projections, a

ribbed portion around the periphery of the plate, said ribs being at an angle to the radii 20 of the plate.

6. A victual-protector for use in the bottom of cooking vessels, consisting of a sheet-metal plate, there being several integral projections extending from the plane of the plate upward, and separate projections extending from the plane of the plate downward, as and for the purpose set forth. 25

In testimony whereof we have signed this specification in the presence of two subscribers. 30
